UNITED STATES PATENT OFFICE

LESLIE STEVENS, OF GLEN RIDGE, NEW JERSEY, ASSIGNOR TO STEVENS MANUFACTURING CORPORATION, OF NEW YORK, N. Y., A CORPORATION OF DELAWARE

DESIGN FOR A LOUD-SPEAKER

Application filed February 11, 1927. Serial No. 20,710. Term of patent 3½ years.

To all whom it may concern:

Be it known that I, LESLIE STEVENS, a citizen of the United States, residing at Glen Ridge, in the county of Essex and State of New Jersey, have invented a new, original, and ornamental Design for a Loud-Speaker, of which the following is a specification, reference being had to the accompanying drawing, forming a part thereof.

Fig. 1 is an edge view, and

Fig. 2 is a face view, of a loud speaker embodying the new design.

The new design comprises as its dominant feature an outwardly bulging circular diaphragm mounted on a back board which extends beyond the periphery of the diaphragm and which is supported in an upright slightly backwardly inclined position.

I claim:

The ornamental design for a loud speaker, as shown and described.

LESLIE STEVENS.
